UNITED STATES PATENT OFFICE.

BRODERICK HASKELL, OF FRANKLIN, PENNSYLVANIA.

BRAKE-BEAM SUPPORT.

Application filed May 15, 1924. Serial No. 713,487.

To all whom it may concern:

Be it known that I, BRODERICK HASKELL, residing at Franklin, in the county of Venango and State of Pennsylvania, a citizen 5 of the United States, have invented or discovered certain new and useful Improvements in Brake-Beam Supports, of which improvements the following is a specification.

The invention described herein relates to 10 certain improvements in the manner of securing to a truck element, rails adapted to serve as supports for brake beams, said rails being supplementary to the usual hangers and more particularly to improvements on 15 the construction described and claimed in the application filed May 15, 1924, Serial Number 713,488. The invention is herein-after more fully described and claimed.

In the accompanying drawings forming a 20 part of this specification, Fig. 1 is a view partly in section and partly in elevation, showing brake beams supporting rails secured to the spring plank of a truck; Fig. 2 is a plan view of the construction shown 25 in Fig. 1; Figs. 3 and 4 are views similar to Fig. 1 illustrating modifications of the manner of attaching the rails to the spring plank; Fig. 5 is a plan view of the construction shown in Fig. 4; Fig. 6 is a detail view 30 of the locking key employed in the construction shown in Figs. 4 and 5; and Fig. 7 is a view similar to Fig. 1 of a further modification of the improvement claimed herein.

35 In the practice of the invention the supporting rails 1 extend in opposite directions from a truck element, as the spring plank 2, sufficiently far to underlie elements of brake beams, as for example, the tension member 40 3 of a truss brake beam. As is well known to those skilled in the art, the brake shoe, when carried by beams supported solely by the usual hanger, will not bear concentrically on the wheels, and hence in order 45 to ensure the proper application of the shoes on the wheels, the portions of the supplementary supporting rails along which the tension member will reciprocate, are upwardly inclined as shown at 4, to so support the brake beam that the curved faces of the shoes will be at all times concentric, or approximately so, with the treads of the wheels.

50 In order to attach the rails to the spring plank, holes 5 are formed therethrough at points adjacent to the flanges 6 along the

edges of the plank to permit of the insertion of toes 7 on the inner ends of the rails. In forming the toes the ends of the rails are so bent as to form shoulders or abutments 8 in 60 such relation to the toes that when the latter has been placed in position and bears on the underside of the plank 2, the shoulders 8 will bear against the inner side of the holes 5 and prevent any inward movement of the 65 rails. Outward movements of the rails are prevented by shoulders or abutments 9 so located on the rails as to bear against the inner faces of the flanges 6 when the rails have been placed in operative position. 70

When the spring plank is formed of channel bars, or of angle bars having high flanges 6^a, as shown in Fig. 3, the inclined portions 4 of the rails extending horizontally from the upper edges of the flanges, would be above the tension member of the brake beam. In such cases, U-shaped bends 10 are so formed in the rails for the reception of the flanges 6^a. The upper portions of the inner legs 11 of the U-shaped bend bear 75 on the inner faces of the flanges and prevent any material outward movements of the rails. The outer legs 12 which extend down along the other faces of the flanges, are made of such lengths that the inclined 80 portions 4 of the rails will be in proper positions relative to the brake beams. It is preferred that the legs 12 should be so bent as to form fulcrums 13 so that the weight 85 of the brake beams on the inclined portions 90 4 will hold the toes 7 in engagement with the spring plank. As the brake beam may, at times, swing upward considerable distances and permit of such upward movements of the outer end of the rails as to 95 shift the lower ends of the legs 11 outward far enough to move the toes into alinement with the holes 5, it is preferred to prevent such movements by means of blocks 14 inserted in the holes 5 outside of the shoulders 8, as shown in Fig. 3. The blocks may be so held on the leg 11 as to be slidable therealong by any suitable means, as for example, by wings 15 on the blocks adapted 100 to be bent around the legs 11. 105

In the construction shown in Figs. 4 and 5, the toes are formed by the ends of hooks formed on the inner ends of the rails and the bottoms of the hooks forming the shoulders or abutments 8^a. These hooks are so formed as to engage the edges of the hole 5^a formed in the web of the spring plank. 110

This hole is made of such a length as to permit of the insertion of the hooks in sequence and said hooks are held in operative position by suitable means such as the key 16, 5 which consists of a plate slit for a suitable distance from opposite ends, thereby forming tongues 17 adapted to be bent over onto the rails. As it is preferred that the portions 18 of the rails adjacent to the hooks 10 should be flat on the web of the spring plank, U-shaped bends 19 are formed for the reception of the flanges 6 of the plank as shown in Figs. 4, 5 and 7.

In lieu of the construction shown in Figs. 15 1 to 5 whereby the inner ends of the supporting rails are held in engagement with the web of the spring plank, such means consisting of tees formed integral with the portions, 8 or 8^a, of the rails projecting through 20 the web of the plank, the locking function of these toes may be effected by means detachable from the portions 8 or 8^a. Such an alternative construction is shown in Fig. 7, the portions 8 and 8^a being extended 25 sufficiently far below the spring plank as shown at 8^b to permit of the passing of a key or gib 20 through the parts below the web.

I claim herein as my invention:—

- 30 1. The combination of a truck element and brake beam supporting elements having their inner end portions arranged above the truck element and extending at right angles from opposite sides of the truck element, the inner ends of the rails being provided with means adapted to detachably engage the truck element and hold the inner end portions of the rails as against vertical movement.
- 35 2. The combination of the spring plank of a car truck, brake beam supporting rails having their inner end portions arranged above the truck element and having their inner ends detachably engaging the spring 40 plank and bearing on the spring plank at points outside of the points of engagement of the inner ends with the plank.

3. The combination of the spring plank of a car truck, brake beam supporting rails provided at their inner ends with portions 50 integral with the rails and adapted to project through the spring plank and means for preventing the withdrawal of such portions from said spring plank

4. The combination of the spring plank 55 of a car truck and brake beam supporting rails provided at their inner ends with portions adapted to be passed through holes in the plank and bear on the underside thereof, said rails bearing on the upper side of the 60 plank at points outside of their attachment to the plank.

5. The combination of a flanged spring plank of a car truck having holes through the web portion thereof, and brake beam 65 supporting rails provided with toes adapted to be passed through the plank and engage the underside thereof, and having shoulders adapted to bear on the flanges of the truck and prevent such movements of the rails as 70 will permit the disengagement of the toes from the plank.

6. The combination of a flanged spring plank having holes through the web portion thereof and brake beam supporting rails provided with toes adapted to be passed 75 through the plank and engage the underside thereof and provided with U-shaped portions for the reception of the flanges on the plank.

7. The combination of a flanged spring plank, brake beam supporting rails having their inner end portions arranged above the plank and provided with portions adapted to project through the web of the plank and having shoulders adapted to bear against the inner faces of the flanges of the plank and means bearing against the underside of the plank and adapted to lock the inner ends 80 of the rails to the plank.

In testimony whereof, I have hereunto set my hand.

BRODERICK HASKELL.

Certificate of Correction.

It is hereby certified that Letters Patent No. 1,537,928, granted May 5, 1925, upon the application of Broderick Haskell, of Franklin, Pennsylvania, for an improvement in "Brake-Beam Supports," were erroneously issued to the inventor, said "Haskell," whereas said Letters Patent should have been issued to *Davis Brake-Beam Company, of Jamastown, Pa., a Corporation of Pennsylvania*, said corporation being owner of the entire interest in said invention, as shown by the records of assignments in this office; and that the said Letters Patent should be read with this correction thereto that the same may conform to the record of the case in the Patent Office.

Signed and sealed this 23d day of June, A. D. 1925.

[SEAL.]

KARL FENNING,
Acting Commissioner of Patents.
